W. W. DEAN

CONTACT ADJUSTING DEVICE

Original Filed July 17, 1918

UNITED STATES PATENT OFFICE.

WILLIAM WARREN DEAN, OF NEWARK, NEW JERSEY, ASSIGNOR TO SPLITDORF ELECTRICAL COMPANY, OF NEWARK, NEW JERSEY, A CORPORATION OF NEW JERSEY.

CONTACT-ADJUSTING DEVICE.

Original application filed July 17, 1918, Serial No. 245,358. Divided and this application filed September 13, 1918. Serial No. 254,012.

To all whom it may concern:

Be it known that I, WILLIAM W. DEAN, a citizen of the United States, residing at Newark, in the county of Essex and State of New Jersey, have invented certain new and useful Improvements in Contact-Adjusting Devices, of which the following is a specification, reference being had to the accompanying drawing.

10 The invention relates to new and useful improvements in centrifugal governors for electric generators, and more particularly to a manually controlled means for varying the action of the centrifugal governor.

15 An object of the invention is to provide devices for effecting minute adjustments in the position of the fixed contact in a centrifugal governor for electric generators.

In the drawings which show by way of 20 illustration, an embodiment of the invention in a governor controlled circuit breaker;

Figure 1 is a view partly in section and partly in side elevation showing an apparatus embodying my improvements; and

25 Figure 2 is a sectional view on the line 2-2 of Figure 1.

The present application is a division of my co-pending application, Serial Number 245,358, filed July 17th, 1918.

30 The invention is directed broadly to devices for effecting minute adjustments in the position of the stationary contact of a governor controlled circuit breaker. The essential features of my improvement consists in a slidable member suitably supported and moved in one direction by yielding means such as a spring while the slidable member is moved in the opposite direction by a rotating part arranged and constructed so as to impart very minute increments of movement to said slidable member. Said rotatable part is provided with a thread which is constructed so as to move the rotatable part endwise by small increments of 35 movement at each fractional part rotation thereof. This rotatable member is provided with a tapered end which bears against the slidable part. Said rotatable part is also located at an angle to the endwise movable member and the tapered part bears against this endwise movable member, so that for each increment of movement imparted to 40 said rotatable part, a fractional portion of

said increment of movement is imparted to said slidable member.

55 The invention will possibly be made more clear by reference to the illustrated embodiment of the invention contained in the drawings. In said drawings, I have shown a supporting table 1, carrying a bracket 2, on which a motor 3 is mounted. The motor shaft 4 projects from the casing and carries a fly wheel 5. Mounted on the bracket 2 is a supporting member 6, preferably made of insulating material. Mounted in the support 6 is an endwise slidable member 7. Said member is formed with a head 8, having the end thereof rounded as at 9. A spring 10 bears against the head at one end and at its other end against a seat in 60 the support 6 and this spring operates to yieldingly force the member 7 endwise in one direction. This endwise slidable member 7 at the free end thereof, serves as a stationary contact of a circuit breaker. 70 The contact surface is indicated at 11 in the drawings. Co-operating with this stationary contact, is a movable contact 12, which is carried by a spring arm 13 clamped to the fly wheel 5 and rotating therewith. 75 The contacts 11 and 12 are disposed in the axis of the rotating shaft of the motor, so that the contact 12 may rotate and still make proper engagement with the contact 11. Mounted on the arm 13 is a weight 14. 80 This weight is disposed considerable at one side of the plane of the member 13, so that as the fly wheel 5 rotates, the centrifugal force acting on the weight 14, will bend the arm 13 and separate the contacts 11 and 12. 85 As a means for shifting the slidable member 7 endwise in a direction opposed to the spring 10, I have provided a manually operated rotatable shaft 15. Said shaft is provided with an enlarged sleeve having a 90 thread 16 cut therein and this threaded sleeve engages a threaded socket 17 formed in the support 6. At the upper end of the shaft 15 there is a knurled hand piece 18, which serves as a means for rotating the 95 shaft 15. The thread on the sleeve 16 is a very fine thread, so that when the shaft is rotated, it will give the shaft small increments of movement in an endwise direction for each partial rotation of the shaft. The 100 lower end of the shaft is cone shaped as in-

dicated at 19 and this cone shaped end bears against the rounded part of the head 8 on the slidable member 7. For each increment of movement in an endwise direction of the 5 shaft 15, there will be imparted to the slid- able member 7, a predetermined fractional portion of said increment of movement. As for example, let us suppose that the shaft 15 by a quarter turn thereof, is moved in 10 an endwise direction one-hundredth of an inch. The tapered end of the shaft 19 may be so shaped as to impart to the slidable member 7 when this increment of movement is given to the shaft, a movement of one 15 ten-thousandth of an inch and so for each one-hundredth of an inch movement of the shaft 15, an endwise movement of one ten- thousandth of an inch is imparted to the slidable member 7. This provides for mi- 20 nute adjustments of the slidable member 7.

With this slidable member embodied in a governor controlled circuit breaker, the speed of the motor may be adjusted very accurately. Furthermore, very small varia- 25 tions in the speed of the motor may be obtained. The mechanism is especially adapted for controlling the speed of a motor driving the record table of a talking machine, wherein it is not only desirable to 30 control the speed of the motor very accurately, but to vary the speed of the motor so as to vary the speed of the record table within very small limits.

The current carrying lines for operating 35 the motor are connected to the terminals 20 and 21. The terminal 20 is connected through the shaft 15 to the slidable member 7 and thus to the contact 11. The contact 20 is connected to the plate 23, against 40 which a brush 24 bears and this brush 24 is connected to the terminal 25. The terminal 25 is connected by the line 26 with one of the brushes of the motor at 27. The terminal 21 is connected through the frame 45 to the other brush of the motor. A resistance R is connected to the terminal 21 and to the shaft 15. It will readily be seen that when the contacts are closed, the resistance R is cut out and the current passes directly 50 to the brushes or motor, while when the contacts 11 and 12 are separated, the resistance

is thrown into the circuit. The contacts are separated as above noted, through the action of centrifugal force on the weight 14. The time at which these contacts separate de- 55 pends upon the position of the contact 11 and this is the part which is capable of being minutely adjusted through my improved devices.

It is obvious that my invention may be 60 embodied in other devices other than that herein described.

Having thus fully described my invention, what I claim as new and desire to secure by Letters Patent, is:-

1. In a contact adjusting device, a pair of contacts, one of which is relatively station- 65 ary, a member carrying said stationary contact slidable endwise for varying the position of the contacts relative to each other, 70 means for yieldingly forcing said member in one direction, means for moving said member in the opposite direction comprising a manually rotatable shaft, means for giving said shaft increments of movement 75 in an endwise direction as it is rotated, and means whereby said shaft at each increment of movement imparts a predetermined frac- 80 tional portion of said increment of movement to said slidable member.

2. In a contact adjusting device, a pair of contacts, one of which is relatively station- 85 ary, a member carrying said stationary contact slidable endwise for varying the position of the contacts relative to each other, 90 means for yieldingly forcing said member in one direction, means for moving said member in the opposite direction comprising a manually rotatable shaft, means for giving said shaft increments of movement in an 95 endwise direction as it is rotated, said slid- able member having a rounded head at the opposite end from the contact carried there- by, said shaft having the end thereof cone- shaped and arranged so as to bear against 100 said rounded head whereby said shaft at each increment of movement imparts a pre- determined fractional portion of said increment of movement to said slidable member.

In testimony whereof I hereunto affix my 100 signature.

WILLIAM WARREN DEAN.
